(57) **CLAIM**

The ornamental design for a dispensing bottle with retractable head, as shown and described.

DESCRIPTION

FIG. 1 is a top perspective view showing my new design for a dispensing bottle with retractable head with the head element in a retracted state;
FIG. 2 is a front view thereof;
FIG. 3 is a back view thereof;
FIG. 4 is a left side view thereof;
FIG. 5 is a right side view thereof;
FIG. 6 is a top side view thereof;
FIG. 7 is a bottom side view thereof;
FIG. 8 is a top perspective view showing the head element in a deployed state;
FIG. 9 is a front view thereof;
FIG. 10 is a back view thereof;
FIG. 11 is a left side view thereof;
FIG. 12 is a right side view thereof;
FIG. 13 is a top side view thereof; and,
FIG. 14 is a bottom side view thereof.

The broken lines of FIGS. 1-14 depict portions of the dispensing bottle with retractable head that form no part of the claimed design.

1 Claim, 14 Drawing Sheets
